MELVIN J. GASKILL, OF PLEASANT PLAIN, OHIO.

Letters Patent No. 87,558, dated March 9, 1869.

IMPROVEMENT IN FENCE.

The Schedule referred to in these Letters Patent and making part of the same.

To all whom it may concern:

Be it known that I, MELVIN J. GASKILL, of Pleasant Plain, in the State of Ohio, have invented a new and useful Improvement in Fence; and I do hereby declare the following to be an exact description thereof, reference being had to the annexed drawings, forming part of this specification.

Figure 1 is a combined section of fence.

Figure 2 is a detached brace or trestle.

Figure 3 is a key.

In the construction of my fence-panel, the rails A A', fig. 1, are held together in the usual manner by battens B B', fig. 1, nailed across the rails, near their ends. These battens may be single or in pairs, to suit convenience.

Two rails in each panel are supporting-rails, A A', fig. 1, and have dovetail notches cut in their under edges, between the battens and the ends of the supporting-rails above described, a a', fig. 1.

In connecting and supporting the several panels of a fence, I construct and join in pairs, triangular rafter-braces, C C, figs. 1 and 2, closed together at the top, and firmly held in their places by cleats D D, figs. 1 and 2, arranged at appropriate distances from the bottom and top of the braces for the reception of the supporting-rails.

These cleats are provided with a tongue, b b, fig. 2, in their centres, to fit the dovetail notch in the ends of the supporting-rails above described, a a, fig. 1.

The braces have a throat also cut out of their under edges, where they join together at the top, C, fig. 2, for the reception of the key E, figs. 1 and 3.

After the panels have been inserted in their places in the braces, the key E is driven through the braces over the supporting-rails, filling the entire space between the upper cleat and the junction of the braces, and forcing the grooved notch, above described, tightly down upon the tongue, and firmly connecting the several panels and braces of a fence in a permanent manner.

What I claim as my invention, and desire to secure by Letters Patent, is—

The arrangement of the dovetail notch, tongue, and throat, in connection with the key, cleats, and triangular braces, operating in such a manner as to permanently join and fasten the several panels and braces of a fence together, substantially as shown and for the purpose specified.

MELVIN J. GASKILL.
